UNITED STATES PATENT OFFICE.

JOHN H. BOOTH, FRANK E. BLAUSEY, AND ARTHUR M. SMITH, OF SAN PEDRO, CALIFORNIA.

CUT-OUT.

No. 884,978.

Specification of Letters Patent.

Patented April 14, 1908.

Application filed January 19, 1906. Serial No. 296,796.

To all whom it may concern:

Be it known that we, JOHN H. BOOTH, FRANK E. BLAUSEY, and ARTHUR M. SMITH, citizens of the United States, and residents of San Pedro, in the county of Los Angeles and State of California, have invented a new and Improved Cut-Out, of which the following is a full, clear, and exact description.

Our invention relates to protective apparatus for telephones and other low-tension circuit instruments, against burning out by the action of lightning or through crosses with lighting or other high-tension circuits.

It consists of the various features and combinations hereinafter described and more particularly claimed.

Reference is to be had to the accompanying drawings forming a part of this specification, in which similar characters of reference indicate corresponding parts in all the views.

Figure 1 is a front elevation of one embodiment of our invention; Fig. 2 is a side elevation thereof; Fig. 3 is a longitudinal, vertical section on the line 3—3 of Fig. 1; Figs. 4, 5 and 6 are perspective views of a contact-arm, a coöperating bracket and one of the ground connections; Fig. 7 shows one of the fuse devices in side elevation, parts being in section, and Fig. 8 illustrates the connections of the apparatus diagrammatically. Fig. 9 is a back view of the supporting plate.

The numeral 10 designates a supporting base for our improved apparatus, which may be of marble, slate or other suitable non-conductor, which has mounted upon it at each side near its center line terminals 11—11, and near its upper portion instrument terminals 12—12 which provide means for connecting, that may be considered, the normal circuit. Joined by conductors 12^a with the line circuit are pairs of metallic lugs 13—13 on which are pivoted arms or conducting members 14—14, there being one for each side of the circuit. Electrically connected with the instrument terminals by conductors 14^a are brackets 15—15 extending outwardly from the base, to which they are secured, and each having an angular end portion 16 in which is a slot 17. This slot is situated nearly opposite a similar slot 18 in the upper extremity of the associated arm 14. The arms are joined to the brackets and held in position to complete the normal circuit by fuses 19, which are shown as surrounded by protecting tubes 20 of glass or other insulat-

ing material. Upon the opposite ends of each of the tubes is a loose metallic cap 21 having projecting from it an annular flange 21^a for engagement with the slotted portions 60 of the bracket and arm at its side of the base. In each of the caps is an opening 22 through which the fuse passes and through which it is free to move, while the end of said fuse is soldered to the cap at 23, there being an intermediate portion 24 which is preferably somewhat separated from the cap. This connection between the fuses, tubes and caps leaves the latter free to separate from the tubes when the fuses are ruptured. 70

Mounted upon the base, within arcing distance of each of the fuse portions 24, is the reduced end 25 of a carbon block 26 furnishing a ground connection for a disruptive discharge, these blocks being joined to a 75 ground terminal 27 by a conductor 28. At the opposite sides of the pivots of the arms from the fuse connections with the brackets are contact members 29—29, into coöperation with which the arms may fall when the 80 blowing-out of the fuses release them. These contacts are connected to the ground terminal by conductors 30. Included between the arms is a spark-gap, furnished by slightly separated carbon blocks 31—31 85 joined to the pivots of the arms by conductors 32.

At the rear of each of the arms is a slot 33 through the base to permit of the passage of an insulating projection 34, which, when 90 drawn outwardly, operates contacts 35 to close the local circuits extending from terminals 36 to a signaling device (not shown).

In the normal condition of the apparatus 95 with the arms held in their raised position by the fuses, the current from the line passes through said arms and fuses to the instrument terminals, this being of too small a volume to break the fuses or produce an arc. 100 At this time the signal circuits are held open by the arm projections. If the line is struck by lightning or sustains a cross with high-tension wires, the current will seek the most readily traversed path to earth and will leap 105 from the caps adjacent to the brackets to the blocks 26, from which a flow to ground occurs over the conductor 28. In case the excess current is on but one side of the line, it is permitted to pass to the opposite arm of the 110 apparatus by leaping across the gap between the blocks 31. The excess flow of current

through the fuses will blow them, thus releasing the caps and freeing the arms. These fall by virtue of their weight and so open the space between them and the brackets (and therefore the instrument circuit) that no arcing can possibly occur. They are received by the contact 29 from which the high-tension current can flow to earth over a circuit of relatively high conductivity, and presenting no impedance. The withdrawal of the arm projections from the local circuit contacts, consequent from the fall of the arms, starts the signal or signals in operation, furnishing an indication at any desired point of the condition of affairs. The high-tension current having ceased to flow, the apparatus may be restored to its initial condition by the application of new fuses to the tubes and caps and their insertion between the raised arms and the brackets.

It will be noted that if there is upon the line a static charge resulting in a discharge sufficient to injure the instrument but of too small volume to blow the fuses in the ordinary manner, the heat of the arc produced by the discharge between the caps and ground connections 26 will melt the portions 24 of the fuses, causing the operation as has already been described.

Having thus described our invention we claim as new and desire to secure by Letters Patent:

1. A cut out comprising a base having line terminals and instrument terminals, said line terminals being below the instrument terminals and comprising lugs, drop levers pivoted to the lugs, said levers having their free ends provided with forks, brackets to which the instrument terminals are connected, said brackets being also provided with forks, fuses resting in the forks and connecting the drop levers with the brackets, carbon blocks having a ground connection connected with the base adjacent to the ends of the fuses resting in the forks of the brackets, a circuit including a signal having its terminals on the base, and arms connected with the drop levers and normally retaining said terminals out of contact with each other.

2. A cut out comprising a base having a line terminal and an instrument terminal, said line terminal being below the instrument terminal and comprising a lug, a drop lever pivoted to the lug, a bracket to which

the instrument terminal is connected, a fuse connecting the bracket and the drop lever, a carbon block having a ground connection connecting with the base adjacent to that end of the fuse connected with the bracket, a circuit including a signal having its terminals on the base, and an arm connected with the drop lever and normally retaining said terminals out of contact with each other.

3. A cut-out comprising a base having a line terminal and an instrument terminal, said line terminal being below the instrument terminal and comprising a lug, a drop lever pivoted to the lug, a fuse connecting the instrument terminal with the free end of the drop lever, a circuit including a signal having its terminals on the base, and an arm connected to the drop lever and normally retaining said terminals out of contact with each other.

4. A cut-out comprising a base having a plurality of line and instrument terminals, drop levers pivoted to the base said line terminals being connected to the drop levers, fuses connecting the instrument terminals and the drop levers, whereby to normally support said drop levers, a circuit including a signal having its terminals on the base, and arms connected with the drop levers and normally retaining said terminals out of contact with each other, said drop levers having a spark gap between them.

5. A cut-out comprising a base having a line terminal and an instrument terminal, a drop lever pivotally mounted on the base said line terminal being connected with the pivotally mounted drop lever, said lever having its free end provided with a fork, a bracket to which the instrument terminal is connected, said bracket being also provided with a fork, a fuse resting in the forks and supporting the drop lever, and a carbon block having a ground connection connected with the cut out adjacent to the end of the fuse which rests in the fork of the bracket.

In testimony whereof we have signed our names to this specification in the presence of two subscribing witnesses.

JOHN H. BOOTH.
